UNITED STATES PATENT OFFICE.

ALOIS BEYER, OF CHICAGO, ILLINOIS.

PORTABLE WATCHMAN'S CLOCK.

No. 877,546.

Specification of Letters Patent.

Patented Jan. 28, 1908.

Application filed April 2, 1906. Serial No. 309,369.

To all whom it may concern:

Be it known that I, ALOIS BEYER, a citizen of the United States, residing at 1109 George street, in the city of Chicago, county of Cook, and State of Illinois, have invented certain new and useful Improvements in Portable Watchmen's Clocks, of which the following is a specification.

My invention relates to portable watchmen's clocks of the kind described in the United States Letters Patent granted to me October 21, 1902, and March 22, 1904, respectively, and numbered 711712 and 755100, which comprise a clock mechanism, a recording mechanism and a number of operating keys located at different stations for making a record on a dial sheet within the clock.

The object of my present invention is to construct a recording mechanism with two separate dial sheets; to secure a double record, one by impression, the other by punctuation, to prevent tampering with the records, and to provide a key and mechanism by which both records are made at one and the same time.

The manner in which I accomplish my object is described in the following specification and illustrated in the accompanying drawings in which:

Figure 1 is a plan view of the back interior of the clock, the lid being open, showing the relative positions of the recording dial, recording mechanism, and key, the key being inserted in the clock in the position in which the record is made. Fig. 2 is a sectional view on the line 2—2 Fig. 1; this view shows the side view of the recording mechanism, the double dial holder and double dials in position in the recording mechanism. Fig. 3 is a central vertical sectional view of the double dial holder and dial sheets in position therein. Fig. 4 is a horizontal section of the dial holder on the line 4—4 Fig. 3. Fig. 5 is an elevation and Fig. 6 a plan view of a ring forming part of the dial holder. Fig. 7 is an elevation and Fig. 8 a sectional view on the line 8—8 Fig. 7 of a cap of the dial holder showing the lock spring attachment, forming part of the cap. Fig. 8^a is a central vertical sectional view of the cap in position one quarter turn from that shown in Fig. 3. Fig. 9 is a top plan view of the frame and part of the recording mechanism therein, two of the top plates being removed. Fig. 10 is a top

plan of the frame with parts broken away 55 showing other parts of the recording mechanism arranged beneath the parts shown in Fig. 9, the key being partly inserted in the frame. Fig. 11 is a plan view similar to Fig. 10, showing the key and recording mechanism in different positions. Fig. 12 is a plan view of the frame and plate over which the top dial sheet passes. Figs. 13 and 14 are perspective views of a lever and rack forming part of the recording mechanism. Fig. 15 is 65 a cross vertical sectional view of the frame and recording mechanism on the line 15—15 Fig. 9. Fig. 16 is sectional view of a flanged collar, needle, adjustable ring and shaft on which the collar slides. Fig. 17 is an end 70 view of Fig. 16 with the ring removed. Fig. 18 is a view of part of the frame and a lever pivoted thereto. Fig. 19 is a gate. Fig. 19^a is a flat gate spring and Figs. 20 and 21, are levers forming parts of the recording mechanism. Fig. 22 is a longitudinal sectional view of the key, the several parts being in the normal position of rest, with the dial sheet in 75 position for recording. Fig. 23 is the same sectional view as Fig. 22 with the parts closed, 80 the jaws being closed on the dial sheet showing the position of the parts when the record is made thereon. Fig. 24 is a sectional view through the center of Fig. 23, the several parts being in the same position, as shown in 85 that figure. Fig. 25 is an enlarged view of the mechanism of the key in the open position of rest, the dotted lines showing the several parts in the closed position. Fig. 26 is an external view of the key showing the 90 key plate on the lower part of the sleeve.

In the drawings A is the casing inclosing the clock, double dial sheets, and recording mechanism, a is the lid which, when closed, is fastened with a lock a¹. In the side of 95 the case A is an aperture a², Figs. 10 and 11, for the admission of the key into the recording mechanism. In the center of this aperture is a cross bar a³, affixed in the frame. On the other side of the case are 100 two eyes a⁴ by which the clock is suspended on the breast of the watchman by a strap. Supported in the center of the face of the case is a clock mechanism inclosed in a case B. The central shaft b of this clock extends 105 beyond the case B to support a double dial holder C—see Figs. 2 and 3. The dial holder consists of a central sleeve c which

fits friction tight on the shaft b . This sleeve is constructed with flanges c^1 and c^2 and two grooves c^3 ; a flanged cylindrical ring c^4 fits on the lower part of said sleeve and is held in place by a flat ring c^5 which is attached to the sleeve by screws c^6 . The ring c^4 is connected to the sleeve by a spring c^7 coiled on the sleeve between the flanges c^1 and c^2 . This spring is attached to the sleeve and ring and is adjusted to hold the stop pin c^8 in the ring against the stop pin in the sleeve and in case the movement of the ring is retarded or stopped while the sleeve continues to revolve, to bring the ring forward to its normal position on the sleeve when the ring is released. An outside cup ring c^{11} fits over the middle of the sleeve and over the ring c^4 . This ring has an annular recess c^{12} in the bottom adapted to admit of the free movement therein of needle points c^{10} . A hole c^{13} in the ring c^{11} is adapted to receive a dowel pin c^{14} which is affixed in the flat ring c^5 by this pin the sleeve c and ring c^{11} are connected together. In the top of this ring are two needle points c^{15} . A cap c^{16} fits over the top of the sleeve and rests on to the top of the cup ring c^{11} , the needle points c^{15} projecting through holes c^{17} in the cap. This cap has a groove c^{18} which extends through on two sides into the center hole of the cap. In this groove is a wire spring c^{19} which projects into the center hole in the cap and fits into the grooves c^3 in the top part of the sleeve, thereby locking the cap and sleeve together—see Figs. 3, 7, 8.

Between the flanged ring c^4 and outside ring c^{11} , is a bottom dial sheet D , which is held in place by the needle points c^{10} . Between the ring c^{11} and the cap c^{16} is a top dial sheet d which is held by the needle points c^{15} —see Figs. 2—3. Bolted to the inside of the case A is a frame E . This frame is constructed of several parts which are firmly secured together. In the central interior of this frame is a key space which registers with the aperture a^2 in the case A adapted to receive the key shown in dotted lines in Fig. 1. On the top of this frame is a cover plate F , Fig. 1, in which there is a slot f^1 . This plate is secured to the frame by screws f^1 . Between the slotted part of this plate and the top of the frame is a space f^2 Fig. 2 & 15, adapted to permit the top dial sheet to rotate therein. Beneath this dial sheet in the frame E is a plate G —see Fig. 12. This plate is flush with the top e of the frame and has a central slot g corresponding with the slot in the plate F . This plate is held in place by a screw g^1 . In the frame E under the plate G is a gate H , see Figs. 9 & 19. The shanks h of this gate lie in channels in the frame and the pivot ends h^1 are held in recesses h^2 in the side of the frame indicated by dotted lines, Fig. 9, in

which they are free to rotate. The part e^1 of the frame E in which the gate lies is of a sufficient depth to allow the free end of the gate to be moved upward to the underside of the plate G . Forming part of this gate is the tongue h^3 which forms an incline surface projecting down through a hole e^2 , in the frame.

Supported in the frame E on the same plane as the gate and parallel thereto is a shaft I . On this shaft and adapted to slide thereon is a flanged collar J . On this collar is a needle j adjustably secured by a ring j^1 attached to the collar; the needle arm j^2 has a vertical point j^3 . Underneath the arm and forming part of the needle is a short projecting finger j^4 . The space between this finger and the arm is adapted to admit the rail h^4 of the gate H , which actuates the needle vertically. The needle is forced back to its normal position by a flat spring h^5 on the gate, and held in position by the gate G . A recess e^3 in the frame E allows the needle to be raised when the plates F and G are removed, so as to permit the rail of the gate to be inserted between the arm and finger and the parts thus connected lowered to their normal position. On the shaft I is a coiled spring adjustably secured thereon by a plug k in the cylindrical part e^4 of the frame E . The pressure of this spring K holds the collar J in the normal position at the end of the shaft as shown in Figs. 9 & 10.

Pivotedly secured in a channel e^5 in the side of the frame E is a rack L , shown in Figs. 10, 11 and 14. This rack lies in the same plane and is parallel with the shaft I and is adapted to be moved into and out of engagement with the beveled flange of the collar J . The pivoted point of this rack is the pin l in the frame E , which passes through the pivot hole in the end of the rack. In a recess in the frame E above the pivot end of the rack is a lever M , shown in Figs. 10, 11, 13 and 18. This lever is pivoted in the frame by the pin m , and is provided with a pin m^1 which extends down through a hole in the frame E into a hole l^1 in the rack whereby the rack is adapted to be actuated by the movement of the free end of the lever. In a recess in the frame E on a plane below the shaft I and spring K is a lever N shown in Figs. 10, 11 and 21, secured by a pivot pin n . One arm n^1 of this lever extends through the side of the frame and has a vertical projection n^2 , the other arm n^3 extends into the space e^6 in the frame and is adapted to be engaged by the key. This lever is held in its normal position by a spring O , which is engaged by the projection n^2 of the lever. This spring lies in the channel e^5 , in the frame, and its free end o rests in the space l^2 between the body of the rack and the arm l^3 , which it engages in its normal position.

In a recess in the frame E underneath the

gate H; a flat triangular lever P is pivotally secured, and is held in its normal position by a spring p attached to the side of the frame by a screw p¹, the arm p² of this lever extends into the space e⁶ and is adapted to be engaged and actuated by the insertion and withdrawal of the key, as shown in Figs. 10 and 11. When actuated by the withdrawal of the key this lever engages the tongue h³ of the gate H and raises the gate. Below the lever N in the frame E is a space Q on the horizontal central line of the key space e⁶ as shown in Figs. 2 and 15, which is adapted to admit the bottom dial sheet D which is free to be revolved therein and to be impressed by the key mechanism as hereinafter described. The key R which is adapted to be securely fastened in a suitable station, has a main case r adapted to hold a slotted slidable sleeve r¹. On one side of the inner end of this sleeve is a projection r² which is engaged by a spring S, the movement of which is limited by the pin r³. Attached to the pin r⁴ secured in the sleeve r¹, and to a pin r⁵ extending through slots r⁶ in the sleeve and secured in the case r is a closed coiled spring T adapted to hold the sleeve in a normal position at the limit of its outward movement in the case, this limit is fixed by the pin r⁶ in the case and the slots r⁶ in the sleeve. Within the sleeve supported on pins r⁷ which extend through slots r⁶ in the sleeve and are affixed in the case r is a wedge block r⁸. The point of this block engages the ends 35 of two spring plates U as shown in Fig. 22. Attached to the other ends of these plates are two impression plates forming jaws u hinged on a pivot pin u¹. The spring plates U are adapted to be moved and to open and close the jaws as shown in Figs. 22, 23 and 40 45 50 55 60 65 70 75 80 85 90 95 100 105 110 115 120 125 130

On one side of the sleeve r¹ is a key plate X having projections x—x³ x⁵ and recesses x¹, x² and x⁴ which like the wards of an ordinary key actuate the recording mechanism. The particular size, position and relation to each other of these parts of the key plate individualize the keys and clocks, in the same manner as ordinary locks and keys are indi-

vidualized to prevent duplication and to thereby obtain security.

When the several parts are constructed as described and illustrated in the drawings, with the clock and recording mechanism attached in position to the interior of the inclosing case A. The sleeve c and flanged ring c⁴ of the dial holder connected by the coiled spring c⁷ and the flat ring c⁵, are adjusted on the clock shaft b. The dial sheet 70 75 D is then inserted in the space Q in the frame E and adjusted on the flanged ring c⁴ as shown in Figs. 2—3. The outside ring c¹¹ is then placed over the sleeve c ring c⁴ and over the needles c¹⁰ which pierce the dial sheet as 80 it is forced into place on the flange ring. The dowel pin c¹⁴ in the flat ring c⁵ enters the hole c¹³ in the ring c¹¹ and locks it with the sleeve c. The dial sheet d is slipped over the end of the sleeve c and the margin inserted between the plates F and G of the recording mechanism. The dial sheet is adjusted in position by pressing the central part over the needle points c¹⁵ onto the top of the ring c¹¹, the needles perforating the dial sheet and projecting 85 above it. The cap c¹⁶ is then slipped over the end of the sleeve c in a position to allow the needle points to enter the needle holes c¹⁷ in the bottom of the cap through which said needle points extend, the bottom of the 90 cap resting on the top of the dial d. In this position the two sides of the spring c¹⁹ are engaged in the grooves c³ in the sleeve c and hold the cap in position on the sleeve and dial as shown in Fig. 3. The flanged ring c⁴ 100 together with the bottom dial sheet D being carried with the sleeve, ring c¹¹ and dial d, by the pressure of the coiled spring c⁷. The dial holder and dials being thus adjusted, the lid of the case is then closed and locked, and the 105 clock is delivered to the watchman ready for use. The keys R, adjusted for this particular clock or clocks, are attached in position at suitable stations, so they can be raised into a horizontal position for use. When the key 110 is in the horizontal position the clock is raised and adjusted so the end of the key enters the key hole a² in the case and frame which are then pressed forcibly over the key as far as possible and then withdrawn therefrom. 115 By this action of the clock on the key the record is made on both dials as follows: When the key enters the key hole space e⁶, the projection x³ of the key plate X moves the lever M and thereby moves the rack L 120 out of contact with the flange of the collar J. The projection x³ then engages the collar J and forces it along the shaft I, thereby compressing the spring K; during this advancing movement the projection x³ engages, moves 125 and passes the arm p² of the lever P, allowing the lever to return instantly to its normal position under the pressure of its spring p. The movement of the key and collar J continuing the end of the key engages the arm 130

n^3 of the lever N and moves it forward. During the movement of the lever N the projection n^2 on the arm n^1 actuates the spring O, and the free end σ of the spring thereby forces the rack into engagement with the flange of the collar J, and holds it at the point on the shaft, where it has been forced by the movement of the key. The clock is then withdrawn from the key. During the receding movement the projection x of the key plate X engages the arm p^2 of the lever P, and carries the arm with it. In this movement the arm of the lever engages and slides over the incline surface of the tongue h^3 of the gate H, and forces it upward, thereby raising the gate. As the gate is thus raised the rail h^4 of the gate forces the arm j^2 of the needle j upward thereby causing the point j^3 of the needle to pass through the slot g in the plate G, and through the dial sheet d, as shown in Fig. 15. At this point the projection X passes the end of the arm p^2 of the lever P which flies back to its normal position thereby releasing the gate which is then pressed back to its normal position by the spring h^5 which is pressed between the top of the gate and the underside of the plate G. As the gate is thus lowered the rail h^4 pressing on the finger j^4 of the needle, forces the point j^3 from the dial sheet and down to its normal position. The key projection x^3 engages and moves the end of the lever M thereby moving the rack outward and releasing the flanged collar J, which under pressure of the spring K flies back to its normal position. This completes the movements of the perforating mechanism.

The movements of the mechanism in the key R which records impressions on the dial sheet D, is as follows. The key enters the clock case and recording mechanism with the jaws locked in the open position and the several parts of the key and its mechanism in the positions shown in Fig. 22. The first movement of the mechanism begins when the projection v^2 of the locking plate is engaged by cross bar a^3 in the frame. The continued advance movement of the clock over the sleeve r^1 forces the ends w of the spring W up the incline edges of the end v^3 of the plate V; the jaws are carried forward clear of the projection v^2 and are then free to be closed, as follows: The advance movement of the sleeve r^1 into the clock being stopped by the cross bar, and movement of the plate V on the hinge pin u^1 , the continued pressure applied by the watchman to the clock forces the sleeve back into the case r. This movement brings the sharp end of the wedge block r^8 between the ends u^4 of the spring plates U and forces them apart thereby closing the jaws and making the impression on the dial sheet D. At the instant this impression is made the end of the spring S in the case 65 snaps off the projecting end of the sleeve

thereby making an alarm which notifies the watchman that sufficient pressure has been applied to the clock and that the record therein has been made. As the clock is withdrawn from the key, the pressure of the coiled spring T forces the sleeve outward in the case to its normal position, the wedge block is thereby withdrawn from the ends of the spring plates, the spring W closes these ends thereby opening the jaws and the ends of the spring close on the end v^3 of the plate V forcing it forward between the jaws and locks them.

The independent action of the dials D and d designed to prevent any successful interference with the record of the clock, operates as follows: The two dial sheets having been adjusted in the dial holder and the dial holder having been adjusted on the shaft of the clock, and the lid closed and locked, the dial d cannot be reached without opening the clock case. The dial sheet D, however, can be reached through the key hole space e^6 . Should this be done and the rotation of the dial sheet be thereby impeded or stopped, the dial sheet D and the flanged ring c^4 and spring c^7 are the only parts affected by the interference. The top dial sheet d and the other parts of the dial holder continue to rotate with the shaft of the clock, until the sleeve c has made almost a complete revolution in the flanged ring c^4 and the stop pin c^9 on the sleeve c is thereby brought in contact with the stop pin c^8 in the flanged ring, and the parts thereby locked together, in which position if the interference is sufficient it will stop both dials and the clock, but this stoppage of the dial d is not possible within 24 hours' time which is required for the clock mechanism to carry the dial d around one complete revolution. Should the interference cease during this space of time, and the dial sheet D be freed therefrom, the coiled spring c^7 immediately carries the ring c^4 back to its normal position on the sleeve c in which the stop pins are in contact.

Having thus described the construction and operation of the several parts of my improved portable watchmen's clock, so that those skilled in the art may understand and construct it, what I claim as new and desire to secure by Letters Patent, is:—

1. In a clock of the kind described, the combination with a main inclosing case having an aperture in the side, of a clock mechanism secured in said case, and a dial holder revolubly supported on the central shaft of said mechanism, said holder consisting of a central sleeve, a ring revolubly supported thereon and having a spring connection therewith, a ring attached to said sleeve and a cap connecting said sleeve and ring, said dial holder having rotatably independent means at either end for holding dials.

2. In a clock of the kind described, the

combination with a main inclosing case, having a key hole in the side, and a clock mechanism secured therein, of a double dial holder supported on the shaft of said mechanism, said dial holder consisting of a sleeve, a ring supported on said sleeve and having a spring connection therewith, and an outer ring and cap, said holder having rotatably independent means at either end for holding dials.

10 3. In a clock of the kind described, the combination with an inclosing case and clock mechanism therein, of a double dial holder consisting of a sleeve, an inner ring revoluble on said sleeve, an outer ring and a cap supported on said sleeve, said holder having rotatably independent means at either end for holding dials.

20 4. In a clock of the kind described, the combination with an inclosable case and clock mechanism therein, of a double dial holder supported on the shaft of said mechanism, said holder consisting of a member adapted to fit on said shaft and be revolved with it, a second member rotatably secured 25 on the first member and having a spring connection therewith, a third member rotatably attached to the first member and revoluble with it, and a fourth member attached to the first and third members and revoluble with them said holder having rotatably independent means at either end for the support of dials.

30 5. In a clock of the kind described, the combination with a clock mechanism in an inclosable case, and a double dial holder supported and rotated by said clock mechanism, said holder having rotatably independent means at either end for holding dials revoluble with it, of a recording mechanism supported in said case adapted to allow said dials to pass through and be marked therein, said mechanism consisting of a frame, a spring pressed needle therein adapted to puncture one of said dials, mechanism adapted 45 to be moved by a key and to raise and lower said needle in said frame, and a key insertible in said case and frame adapted to actuate said needle and thereby puncture one of said dials, and an impression mechanism 50 in said key adapted to be actuated by pressure applied thereto in the insertion of said key in said frame and to engage and impress the other dial.

60 6. In a clock of the kind described the combination with a clock mechanism, and a recording mechanism in an inclosable case; of a double dial holder adjustably supported on the central shaft of said clock mechanism, said holder consisting of a member adapted 65 to fit friction tight on said shaft and to revolve with it, a second member secured on the first member and adapted to be revolved with it and to have its movement retarded or stopped for a limited time, a spring connecting

said members, a third member attached to the first member and movable with it, and a fourth member attached to the first and third members and movable with them; the second and third members being adapted to support a dial sheet, and the third and fourth members being adapted to support a second dial sheet; said dial sheets when supported in said holder being adapted to extend into said recording mechanism in said case, substantially as described and for the purposes 75 specified.

7. In a clock of the kind described the combination with a clock mechanism, a recording mechanism, and an inclosable case, of a double dial holder, adjustably supported 80 on the central shaft of said clock mechanism and revoluble with it, said holder being adapted to support a pair of dial sheets, revoluble with it, a part of said holder being adapted to allow the movement of one of 85 said dial sheets to be retarded or stopped, independent of the rotation of the other part of said holder and the other dial sheet supported thereon; means connecting said parts adapted to return the retarded part to its 90 normal position when released from interference; said dial sheets in said holder being adapted to pass through said recording mechanism substantially as described and for the purposes specified. 95

8. In a clock of the kind described the combination with a clock mechanism, a double dial holder attached to and revoluble with said mechanism, said dial holder being adapted to hold a pair of dial sheets, 100 and to rotate said sheets together, or independently, and a recording mechanism adapted to puncture one of said dial sheets; with a key insertible in said mechanism adapted to actuate and cause said recording 105 mechanism to puncture one of said sheets; said key containing a mechanism adapted to be actuated by pressure applied thereto during its advance into said recording mechanism in said clock, and to engage and impress the 110 other dial sheet supported in said dial holder, substantially as described and for the purposes specified.

9. In a device of the kind described the combination comprising an inclosable case, 115 a clock mechanism therein, a double dial holder attached to and rotatable with said mechanism adapted to support and rotate a pair of dial sheets, a recording mechanism actuated by a key and adapted to puncture 120 one of said dial sheets; a key insertible in said case and recording mechanism adapted to operate said recording mechanism; a recording mechanism supported in said key adapted to be actuated by the insertion and retraction of said key into said case and recording mechanism, and to thereby engage 125 and impress the other dial sheet supported

6 by said dial holder, substantially as described and for the purposes specified.

10. In a clock of the kind described the combination with a clock mechanism, and a 5 recording mechanism; of a double dial holder adapted to support and rotate a pair of dial sheets independently of each other, in said

recording mechanism, substantially as described and for the purposes specified.

ALOIS BEYER.
